Inventor:
Henry R. Gogay
My attorney
Montgomery Ward

UNITED STATES PATENT OFFICE.

HENRY R. GOGAY, OF COLUMBUS, OHIO, ASSIGNOR TO SOLAR METAL PRODUCTS COMPANY, INC.

HOLLOW METAL DOOR.

1,323,756.

Specification of Letters Patent.

Patented Dec. 2, 1919.

Application filed October 24, 1917. Serial No. 198,267.

To all whom it may concern:

Be it known that I, HENRY R. GOGAY, a subject of the Crown of Great Britain, and resident of Columbus, in the county of 5 Franklin and State of Ohio, have invented a new and useful Improvement in Hollow Metal Doors, of which the following is a specification.

In the manufacture of hollow metal doors 10 it has heretofore been impractical to complete the door until the hinge to be used in connection therewith was known, thus preventing the stocking up of a large supply of doors and also requiring a special set of dies 15 and tools for each particular size and style of hinge.

The object of my invention is to produce a type of hollow metal door which may be completed in large quantities irrespective of 20 the size and type of hinge to be used, thus materially reducing the cost of manufacture and also permitting the rapid filling of orders from stock.

These results are accomplished by blanking 25 out a sub-holder to fit a particular hinge wing, providing a backing carried by the sub-holder and extending across its blanked out portion, to which backing the hinge wing may be secured, and blanking out the 30 edge of the hinge stile to fit the sub-holder, means being employed for securing the sub-holder to the hinge stile.

A practical embodiment of my invention 35 is represented in the accompanying drawings in which,

Figure 1 represents a portion of a door in edge elevation with my invention applied thereto,

Fig. 2 is a side view of the same, partly in 40 section,

Fig. 3 is a section taken in the plane of the line III—III of Fig. 2, and

Fig. 4 is a section taken in the plane of the line IV—IV of Fig. 1.

45 The edge 1 of the hinge stile 2 of the door is blanked out to fit a sub-holder 3, preferably channel-shaped, which sub-holder is secured in the blanked out portion of the edge of the door by any suitable means, such, for 50 instance, as by means of upper and lower clips 4, 5, spot-welded as indicated by the dotted circles 4*, 5* to the edge of the hinge stile and overlapping the top and bottom of the sub-holder. Screws 6, 7, are used for securing the top and bottom of the sub-holder

to the overlapping portions of the clips 4, 5, The sub-holder is blanked out to fit the particular hinge wing 8 to be used in connection with the door. A backing 9 extends across the blanked out portion of the sub-holder 60 and is spaced therefrom for a considerable distance to accommodate hinge wings of various sizes. This backing 9 may be secured to the sub-holder 3 at the top and bottom of the backing as by being spot-welded as indicated by the dotted circles 9* to the said sub-holder. The hinge wing is secured to the backing 9 by screws 10.

If necessary, shims 11 may be interposed between the hinge wing 8 and the backing to 70 accommodate wings of different thicknesses to bring the face of the wing flush with the edge of the hinge stile and the face of the sub-holder.

While I have shown my invention as applied to the attachment of a hinge to a door, it is obvious that the same means may be employed for attaching the hinge to the door frame, without departing from the spirit and scope of my invention; hence I intend to 80 cover this application in any hollow metal structure where a hinge is to be used.

What I claim is:

1. In a hollow metal door arranged to receive hinge wings of various sizes and styles, 85 a sub-holder blanked out to fit a particular hinge wing, a backing carried by the sub-holder extending across its blanked out portion, a hinge stile having its edge blanked out to fit the sub-holder, and means for securing the hinge wing to the backing.

2. In a hollow metal door arranged to receive hinge wings of various sizes and styles, 95 a sub-holder blanked out to fit a particular hinge wing, a backing carried by the sub-holder extending across its blanked out portion, a hinge stile having its edge blanked out to fit the sub-holder, and means for securing the sub-holder to the stile.

3. In a hollow metal door arranged to receive hinge wings of various sizes and styles, 100 a sub-holder blanked out to fit a particular hinge wing, a backing carried by the sub-holder extending across its blanked out portion, a hinge stile having its edge blanked out to fit the sub-holder, means for securing the hinge wing to the backing, and means for securing the sub-holder to the stile.

4. In a hollow metal door arranged to receive hinge wings of various sizes and styles, 110

a channel-shaped sub-holder blanked out to fit a particular hinge wing, a backing carried by the sub-holder extending across its blanked out portion, a hinge stile having its edge blanked out to fit the sub-holder, and means for securing the hinge wing to the backing.

5. In a hollow metal door arranged to receive hinge wings of various sizes and styles, a channel-shaped sub-holder blanked out to fit a particular hinge wing, a backing carried by the sub-holder extending across its blanked out portion, a hinge stile having its edge blanked out to fit the sub-holder, and means for securing the sub-holder to the stile.

10. In a hollow metal door arranged to receive hinge wings of various sizes and styles, a channel-shaped sub-holder blanked out to fit a particular hinge wing, a backing carried by the sub-holder extending across its blanked out portion, a hinge stile having its

edge blanked out to fit the sub-holder, means for securing the hinge wing to the backing, and means for securing the sub-holder to the 25 stile.

15. In a hollow metal door arranged to receive hinge wings of various sizes and styles, a sub-holder blanked out to fit a particular hinge wing, a backing carried by the sub- 30 holder extending across its blanked out portion and spaced from the sub-holder for a sufficient distance to accommodate hinge wings of various sizes and styles, a hinge stile having its edge blanked out to fit the 35 sub-holder, clips carried by the edge of the hinge stile overlapping the top and bottom of the sub-holder and screws engaging the sub-holder and clips for securing the sub- 40 holder to the stile.

In testimony, that I claim the foregoing as my invention, I have signed my name this 29th day of September 1917.

HENRY R. GOGAY.
